CONDENSER

Filed July 27, 1922

UNITED STATES PATENT OFFICE

GEORGE L. MACNEILL, OF WILKINSBURG, PENNSYLVANIA, ASSIGNOR TO ELLIOTT COMPANY, OF PITTSBURGH, PENNSYLVANIA, A CORPORATION OF PENNSYLVANIA

CONDENSER

Application filed July 27, 1922. Serial No. 577,862.

My invention relates to condensers, and particularly to surface condensers and also to methods of operating the same to increase the efficiency thereof.

Heretofore, it has been customary to so build and operate condensers, and more particularly condensers of the surface type, that the temperature of the condensate formed thereby is lowered to such a point that considerable heat energy is required to reconvert the condensate into steam. This objection has been appreciated heretofore, and attempts have been made to overcome the same. For this purpose condensers have been constructed with a hot well, and with a steam by-pass leading thereto for heating the condensate in the hot well, there being a hydrostatic trap for preventing the steam by-passed around the condenser from entering the condenser through the outlet port. In such constructions, however, there has been no means provided for getting rid of the air in the hot well. This soon resulted in the hot well becoming air bound, thereby preventing any further transfer of steam through the by-pass.

It has also been proposed to construct condensers with the tube nest eccentrically disposed with respect to the condenser shell to provide an efficient steam flow path, and to permit the tubes to be practically surrounded by steam, or other fluid to be condensed, at substantially the temperature at which it enters the condenser. This has made it necessary for any liquid of condensation falling from the nest of tubes to pass through this uncondensed steam, or fluid, and therefore take up heat from the steam or fluid and be delivered at approximately the temperature of the steam or fluid through which it falls. Such constructions, however, have not provided a separate heating chamber in which an effective heat transfer might take place.

In my present invention, there is provided a condenser of improved construction operating in a novel manner, whereby the efficiency is greatly increased from a heat conservation standpoint, and the objections to existing constructions effectively overcome.

In the accompanying drawings, there is

shown for purposes of illustration only, a condenser embodying my invention, it being understood that the drawings do not define the limits of my invention, as changes may be made in the construction and operation disclosed without departing from the spirit or scope of the same.

Figure 1 of the drawings is a transverse sectional view, largely diagrammatic, illustrating one embodiment of the present invention, the section being taken on the line 1—1 of Figure 2.

Figure 2 is a vertical longitudinal sectional view taken on the line II—II of Figure 1 and

Fig. 3 is a view taken along the line III—III of Fig. 1.

At the present time, it is customary to construct surface condensers in such manner that the steam enters the nest of tubes at one portion, usually at the top, traverses the nest of tubes, and is gradually condensed during its passage over the tubes. After traversing the nest of tubes, the vapor content is practically eliminated so that nothing remains but a small amount of vapor and the non-condensable gases. These gases are then removed from the condenser by the provision of a suitable vacuum producing means. The point of gas off-take is usually located at the lowest part of the condenser and in this portion of the condenser there obviously exists the lowest pressure and temperature.

During the passage of the steam and non-condensable gases through the nest of tubes in the condenser, there is some loss of pressure, so that while a very low pressure may exist within the condenser adjacent the point of gas off-take, the pressure is usually relatively higher at the point where the steam and gases enter the nest of tubes. By reason of the low pressure at the point of gas off-take the temperature at this point is also necessarily lower. This is due partly to the decreased pressure and partly to the decrease in the vapor content. Inasmuch as the point of gas off-take is generally at the lowest portion of the condenser, the condensate in dripping through this region assumes the temperature of the vapor at this point. This neces-

sarily reduces the temperature of condensate materially below that of the incoming steam.

Inasmuch as the condensate from surface condensers is generally pumped back into the boilers to be converted again into steam, it is apparent that considerable heat energy will again be required to evaporate this cold condensate in the boilers. By the present invention, the temperature of the condensate is materially raised, thereby making it unnecessary to expend as large an amount of energy in the boilers for reconverting the same into steam. The condensate is heated to such a degree that it is de-aerated. This is desirable as it prevents oxidation of boiler tubes.

As illustrated in the accompanying drawing, a condenser embodying the present invention may comprise a condenser shell 2, having a steam inlet 3 adapted to receive steam from any desired source, such as a steam engine, steam turbine or other form of apparatus. Extending longitudinally of the condenser shell, and providing a passage 4 leading directly from the steam inlet 3, is a pair of spaced plates 5. On opposite sides of the plates 5 may be arranged tube nests 6 as indicated. For sake of clearness, the tube nests are indicated diagrammatically only, it being apparent that the number and arrangement of tubes may be varied as desired. Part of the steam entering the condenser shell 2 will pass through the tube nests 6 to the lower portion of the condenser shell. During this passage the major portion of the steam will be condensed whereby at the termination of the flow path through the condenser there will exist only a comparatively small amount of vapor, together with the non-condensable gas content. This remaining vapor, together with the non-condensable gases, may be withdrawn from the condenser through openings 7 communicating with an off-take connection 8 leading to a vacuum producing means of any well-known construction. This flow will take place around baffles 9 secured to the plates 5 and overlying the openings 7.

The condensate formed in the condenser will pass through perforations in the plate 10 into the heating chamber 11. Communicating with this heating chamber is the conduit 4 which conducts steam directly from the inlet 3 to the heating chamber. This chamber constitutes in effect a jet condenser operating in parallel with the surface condenser, and in which the condensing water is the cold condensate coming from the surface condenser. This condensate condenses a portion of the steam in the heating chamber 11 and in so doing is heated up to the steam temperature and is thereby de-aerated. In order to provide for the off-take of the accumulated gas which is left after the vapor is condensed in the chamber 11 to prevent the same from becoming air bound, the heating chamber is

formed with any desired number of escape openings 12.

It will be apparent that the condenser shell may be provided with a header 13 of any desired construction for supplying cooling water to the tubes in the nests 6, and that this cooling water after passing through the lower bank of tubes will enter the reversing box 14 from which it will be directed into the upper bank of tubes.

The heating chamber 11 may also be provided with a hot well 15 from which the condensate may be led to the desired boiler or other apparatus.

By reason of the provision of means for causing the condensate to be directly subjected, in a specially provided heating chamber, to the action of steam before the passage of the condensate from the condenser, it will be obvious that the condensate is maintained at the highest possible temperature thereby materially increasing the efficiency of the apparatus by decreasing the amount of heat energy which will be required in reconverting it into steam. The high temperature of the condensate causes it to be de-aerated which is desirable to prevent oxidation of boiler tubes.

The advantages of the present invention arise from the provision of efficient means for causing the condensate to leave the condenser at the highest possible temperature.

Further advantages arise from the provision of a separate heating chamber having means for preventing the same from becoming air bound, and from the respective and relative locations of the outlet for non-condensable gases from the condenser and heating chamber.

I claim as my invention:

1. In a condenser, a shell having a heating chamber therein, two tube nests disposed above the heating chamber, and a conduit between the tube nests for passing steam independently of the tube nests into the heating chamber to raise the temperature of the water therein, said condenser and said chamber each having a gas take-off communicating therewith and located adjacent the termini of their respective condensing zones.

2. A surface condenser comprising a single shell, a tube nest therein, a heating chamber below the tube nest also disposed therein, a conduit also disposed in the shell for passing steam independently of the tube nest to the heating chamber and means secured to the conduit for conducting non-condensable gases outside the condenser shell.

3. In a surface condenser, a shell having a plurality of tube nests therein, a heating chamber within the shell below the tube nests, means extending between the tube nests for passing steam independently thereof into the heating chamber, and means for permitting the escape of gases from the heating chamber to the tube nests.

4. In a surface condenser, a shell having two nests of tubes therein, a heating chamber within the shell below the tube nests, a conduit separating said tube nests for passing steam independently thereof to the heating chamber, and means for permitting the escape of vapors from the heating chamber to the tube nests. 70
5. In a surface condenser, a shell having two nests of tubes therein, a heating chamber within the shell below the tube nests, a conduit between the tube nests for conducting steam independently thereof to the heating chamber, means for causing a divided flow of condensate from the tube nests to mingle with the steam within the heating chamber, thereby heating the condensate, means for permitting the escape of vapors from the heating chamber to the tube nests, and means communicating with the tube nests at the points of flow termination therein for conducting non-condensable gases to a point outside the condenser shell. 75
6. In a surface condenser, a shell having two nests of tubes therein, a heating chamber within the shell below the tube nests, a conduit between said tube nests for conducting steam independently thereof to the heating chamber, means for causing a divided flow of condensate from the tube nests to mingle with the steam within the heating chamber, thereby heating the condensate, means adjacent the point of steam flow termination within the heating chamber for permitting the escape of vapors from the heating chamber to the tube nests and means communicating with the tube nests at the points of flow termination therein for conducting non-condensable gases from within the condenser, said means being at least partially supported by said conduit. 90
7. In a condenser, a shell having a heating chamber therein, tubes above the heating chamber, there being a passageway between said tubes dividing the same into separated nests, said passageway being constructed to pass steam between the nests into the heating chamber to raise the temperature of the water therein, said condenser and said chamber each having gas take-off means communicating therewith and located adjacent the flow terminus of the tube nests, the gas offtake means for said chamber discharging into the tube space thereabove. 100
8. The combination with a surface condenser shell in which the degree of vacuum increases progressively from the point of steam entrance to the region of air outlet, of a reheater for the condensate included within said shell, a steam supply passageway adapted to draw steam from the surface condenser at a point of relatively high absolute pressure, and a vent for air and non-condensable gases from the reheater to a region of the main condenser not at the lowest absolute pressure. 110
9. The combination with a surface condenser shell in which the degree of vacuum increases progressively from the point of steam entrance to the region of air outlet, of a reheater which heats by direct contact of water and vapor included within the condenser shell, a steam supply passageway adapted to draw steam from the surface condenser at a point of relatively high absolute pressure, and a vent for air and non-condensable gases from the reheater to a region of the main condenser not at the lowest absolute pressure. 115
10. The combination with a surface condenser shell in which the degree of vacuum increases progressively from the point of steam entrance to the region of air outlet, of a reheater for the condensate within the condenser shell, a steam supply passageway also located within the condenser shell and adapted to draw steam from the surface condenser at a point of relatively high absolute pressure, and a vent for air and non-condensable gases from the reheater to a region of the main condenser not at the lowest absolute pressure. 120
11. The combination with a main condenser in which the degree of vacuum increases progressively from the point of steam entrance to the region of air outlet, of a reheater for the condensate from the surface condenser, a steam supply passageway located entirely within said condenser and adapted to draw steam therefrom at a point of relatively high absolute pressure and deliver the same to said reheater, and a vent for air and non-condensable gases from the reheater to a region of the main condenser not at the lowest absolute pressure. 125
12. The combination with a main surface condenser in which the degree of vacuum increases progressively from the point of steam entrance to the region of air outlet, of a reheater for the condensate from the surface condenser, a steam supply passageway located within the condenser and adapted to draw steam therefrom at a point of relatively high absolute pressure, and a vent for air and non-condensable gases from the reheater to a point adjacent the flow terminus of the condenser. 130
13. The combination with a main surface condenser in which the degree of vacuum increases progressively from the point of steam entrance to the region of air outlet, of a reheater for the condensate from the surface condenser, a steam supply passageway located within the condenser and adapted to draw steam therefrom at a point of relatively high absolute pressure, a vent for air and non-condensable gases from the reheater to a point adjacent the flow terminus of the condenser, and means for cooling at least a portion of the non-condensable gases withdrawn. 130
14. A surface condenser comprising a sin-

gle shell, a tube nest therein, a heating chamber below the tube nest, a conduit disposed in the shell for passing steam independently of the tube nest to the heating chamber, and 5 means secured to the conduit for conducting non-condensable gases outside the condenser shell.

15. In a surface condenser, a shell having a plurality of tube nests therein, a heating chamber below the tube nests for receiving 10 condensate therefrom, means within the condenser extending between the tube nests for passing steam independently thereof into the heating chamber for heating the condensate 15 therein, and means permitting the escape of gases from the heating chamber to the tube nests.

16. In a surface condenser, a shell having a plurality of tube nests therein, a heating chamber below the tube nests for receiving 20 condensate therefrom, means within the condenser extending between the tube nests for passing steam independently thereof into the heating chamber for heating the condensate 25 therein, means permitting the escape of gases from the heating chamber to the tube nests, and means for cooling at least a portion of the non-condensable gases withdrawn.

17. In a surface condenser, a shell having 30 two nests of tubes therein, a heating chamber below the tube nests for receiving condensate therefrom, a conduit within the condenser separating said tube nests for passing steam independently thereof to the heating chamber, and means permitting the escape of vapors from the heating chamber to the tube nests.

18. In a surface condenser, a shell having 40 two nests of tubes therein, a heating chamber below the tube nests for receiving condensate therefrom, there being a steam passageway within the condenser between the tube nests for passing steam independently of the tube nests to the heating chamber, and means permitting the escape of vapors from the heating chamber into the tube nests.

19. In a surface condenser, a shell having two nests of tubes therein, a heating chamber below the tube nests, a conduit between the 50 tube nests for conducting steam independently thereof to the heating chamber, means for causing a divided flow of condensate from the tube nests to mingle with the steam within the heating chamber, thereby heating the 55 condensate, means for permitting the escape of vapors from the heating chamber to the tube nests, and means communicating with the tube nests at the point of flow termination therein for conducting non-condensable gases 60 to a point outside the condenser shell.

20. In a surface condenser, a shell having two nests of tubes therein, a heating chamber below the tube nests for receiving condensate 65 therefrom, there being a passageway within the surface condenser between the tube nests

for conducting steam directly to the heating chamber, means for causing a divided flow of condensate from the tube nests to mingle with the steam within the heating chamber, thereby heating the condensate, means permitting the escape of vapors from the heating chamber into the tube nests, and means communicating with the tube nests adjacent the flow terminus thereof for conducting non-condensable gases therefrom to a point outside 75 the condenser shell.

21. In a condenser, a shell having a tube nest therein, a conduit for conducting fluid to a zone below said tube nest, and means at least partly supported by said conduit for conducting non-condensable gases to a point 80 on one side of a longitudinally extending vertically disposed median plane.

22. In a condenser, a shell having a tube nest therein, a heating chamber within the 85 shell below said tube nest, a conduit for conducting fluid to said heating chamber, and means at least partly supported by said conduit for conducting non-condensable gases from said heating chamber to a point outside 90 of the condenser shell.

23. In a surface condenser, a shell having a plurality of tube nests therein, a heating chamber within the shell below the tube nests, means extending between the tube nests for 95 passing steam independently thereof into the heating chamber, means for permitting the escape of gases from the heating chamber to the tube nests, and means for conducting such gases to a point outside of the condenser shell.

24. In a condenser, a shell having a tube nest therein, a conduit for conducting vapor to a point adjacent the flow terminus of the tube nest, and means extending outwardly 100 from the interior of said condenser to the outside thereof for withdrawing the non-condensable gases therefrom.

In testimony whereof, I have hereunto 105 subscribed my name this 24th day of July, 1922.

GEORGE L. MACNEILL.
